US00D474280S

(12) **United States Design Patent** (10) Patent No.: **US D474,280 S**
(45) Date of Patent: **** May 6, 2003**

(54) **ANALYZER**

(75) Inventors: **R. Sam Niedbala**, Allentown, PA (US);
Michael J. Gausling, Bethlehem, PA (US); **Philip Michael Formica**, Center Valley, PA (US); **John W. Scott**, Perkasie, PA (US)

(73) Assignee: **Orasure Technologies, Inc.**, Bethlehem, PA (US)

(**) Term: **14 Years**

(21) Appl. No.: **29/167,200**

(22) Filed: **Sep. 11, 2002**

Related U.S. Application Data

(62) Division of application No. 29/148,789, filed on Sep. 28, 2001.

(51) **LOC (7) Cl. 24-01**

(52) **U.S. Cl. D24/232; D24/231**

(57) **CLAIM**

The ornamental design for an analyzer, as shown and described.

DESCRIPTION

FIG. 1 is a perspective view of a first embodiment of an analyzer according to our new design;

FIG. 2 is a front view of the analyzer of FIG. 1;

FIG. 3 is a rear view of the analyzer of FIG. 1;

FIG. 4 is a top view of the analyzer of FIG. 1;

FIG. 5 is a bottom view of the analyzer of FIG. 1; and,

FIG. 6 is a left side view of the analyzer of FIG. 1, the right side being a mirror image thereof.

1 Claim, 3 Drawing Sheets
